BY J. Shandon Bell.

ATTORNEY.

UNITED STATES PATENT OFFICE.

DANIEL W. PEDRICK, OF PHILADELPHIA, PENNSYLVANIA, ASSIGNOR TO
PEDRICK & AYER, OF SAME PLACE.

MACHINE FOR TURNING WRIST-PINS.

SPECIFICATION forming part of Letters Patent No. 308,925, dated December 9, 1884.

Application filed April 24, 1884. (No model.)

To all whom it may concern:

Be it known that I, DANIEL W. PEDRICK, of the city and county of Philadelphia, in the State of Pennsylvania, have invented certain new and useful Improvements in Apparatus for Turning Wrist-Pins, Crank-Pins, &c., of which improvements the following is a specification.

The object of my invention, which is an improvement upon that for which Letters Patent of the United States No. 78,733 were granted and issued to Theodore A. Goff, under date of June 9, 1868, is to insure a regular and uniform longitudinal feed of the cutter, and in effecting such feed to prevent cramping or binding between the case of the cutter-ring and the guides thereof by equalizing the application of power to the former on opposite sides of its center.

The improvements claimed are hereinafter fully set forth.

In the accompanying drawings, Figure 1 is a view in perspective of an apparatus for turning wrist-pins, crank-pins, &c., embodying my invention; Fig. 2, a side view, partly in elevation and partly in section, of the same; Fig. 3, an end view in elevation as seen from the left, and Fig. 4 a transverse section at the line $x-x$ of Fig. 2.

In the practice of my invention I construct the frame of the machine substantially as in Patent No. 78,733, before referred to, a pair of end pieces, 1 1, being located in parallel planes, and united at a proper distance apart by bolts 2 2, which serve both as connecting-pieces and as guides for the cutter-case, said bolts having collars or shoulders 3 3 adjacent to their ends, against which collars the inner faces of the end pieces, 1 1, abut, and are held firmly thereto by nuts 4 4, engaging threads on the bolts 2 2. Center screws, 5 5, having proper center-points on their inner ends, are fitted in the end pieces, 1 1, in line axially one with another, and with a cutter-ring, 6, in which the tools or cutters 7 are secured, and serve to attach the machine to the cross-head or other piece on which the wrist or crank pin to be turned is located. The cutter-ring 6 is divided diametrically into two sections, which are united in any suitable manner—as by dowel-pins 9—and is mounted, with the capacity

of free rotation, in a circular opening formed in a cutter-case, 8, which is likewise formed in two sections united by bolts 10 and nuts 11, and the cutters 7 are secured by set-screws in dovetailed radial grooves in the sections. The cutter-case 8 is fitted on the guide-bolts 2 of the frame so as to be movable longitudinally thereon, and its opening, which forms the seat of the cutter-ring, is located in line axially with the center screws, 5. The cutter ring and case are by such construction adapted to be removed from and replaced in the frame, so as to enable the cutter-ring to inclose the pin on which its cutters are to operate, such operation being effected by the rotation of the cutter-ring and cutters while the pin and frame of the machine are stationary.

Rotation is imparted to the cutter-ring from a driving-shaft, 12, fitted in bearings in the end pieces, 1, of the frame, and carrying a crank, 13, for the application of manual power. A pulley or gear may be substituted for the crank, if desired, and the shaft rotated from any suitable prime mover. A spur-gear, 14, having an internal key or feather fitting a longitudinal spline upon the driving-shaft 12, meshes with a pinion, 15, mounted in bearings in the cutter-case 8, which is recessed to admit the gear 14, and the pinion 15 in turn engages the teeth of a gear, 16, formed upon the periphery of the cutter-ring 6. The requisite longitudinal traverse or feed of the cutter-case and cutters is imparted thereto primarily from the rotation of the driving-shaft through a pair of feed-shafts, 17 18, which are mounted in bearings in the end pieces, 1, on opposite sides of and at equal distances from the axis of the cutter-ring, and are threaded between their bearings, their threads engaging corresponding female threads in the cutter-case 8. A spur-pinion, 19, on the driving-shaft through intermediate gears, presently to be described, rotates a gear, 20, fixed on the upper feed-shaft, 17, which is mounted in bearings in the end pieces of the frame, and the gear 20, through an idle gear, 21, turning on one of the center screws, 5, rotates a gear, 22, of corresponding diameter and pitch, secured upon the opposite feed-shaft, 18. The application of power to the cutter-case, in the longitudinal movements thereof, is thus effected equally on opposite sides of the cutter.

ring, and an equal bearing of the case upon the guide-bolts is maintained, with a corresponding avoidance of cramping or undue friction and wear thereon. The feed-shafts 17 5 18 are rotated coincidently in one or the other direction, respectively, as required to move the cutter-case alternately toward each of the end pieces of the frame at the completion of its traverse in the opposite direction, 10 according as one or the other of two pinions, 23 24, is caused to mesh with the gear 20 of the feed-shaft 17. To this end the pinions 23 24 are mounted loosely on studs upon opposite arms of a double-armed shifting-lever, 25, 15 which is journaled on the end of the driving-shaft adjacent to the feed-gear 20, the pinion 23 meshing with the pinion 19 on the driving-shaft 12, and the pinion 24 with an idle-pinion, 26, on the shifting-lever, said idle-pinion 20 in turn meshing with the pinion 19. It will thus be seen that the pinions 23 and 24 will be rotated continuously and in opposite directions during the rotation of the driving-shaft, and by moving the shifting-lever 25 axially 25 thereon in one or the other direction either of the pinions 23 and 24 may be engaged with the gear 20, and will impart thereto, and thence to the feed-shafts 17 18, rotation proper to feed the cutter-case in the direction desired; 30 or the longitudinal feed may be stopped by moving both of said pinions out of engagement with the gear 20.

The shifting-lever may be fixed in either position by a clamping-nut, 29, engaging a thread 35 on the end of a stud, 28, fixed in the adjacent end piece, 1, and passing through a segmental slot, 27, formed in one of the arms of the shifting-lever and curved concentrically with the driving-shaft.

40 I claim as my invention and desire to secure by Letters Patent—

1. In an apparatus for turning wrist or crank pins, the combination, substantially as set forth, of a frame, a cutter-case fitted to move longitudinally on guides therein, a cutter-ring fitting in said case, a driving-shaft which rotates said cutter-ring, and a pair of threaded feed-shafts rotated by the driving-shaft and engaging the cutter-case on opposite sides of the cutter-ring, respectively. 45 50

2. In an apparatus for turning wrist or crank pins, the combination, substantially as set forth, of a pair of end frame-pieces, a pair of guide-bolts connecting said end pieces at opposite sides, a cutter-case fitted to move longitudinally on said guide-bolts, a cutter-ring adapted to rotate in said case, a driving-shaft which rotates said cutter-ring, a pair of feed-shafts having screw-threads which engage the cutter-case on opposite sides of the cutter-ring, 55 respectively, and gearing for imparting coincident rotation to said feed shafts from the driving-shaft. 60

3. In an apparatus for turning wrist or crank pins, the combination, substantially as set forth, of a frame, a cutter-case fitted to move longitudinally on guides therein, a cutter-ring fitting in said case, a driving-shaft which rotates said cutter-ring, a threaded feed-shaft engaging said cutter-case, a double-armed shifting-lever journaled on the driving-shaft, and two driving-pinions mounted on opposite arms of said shifting-lever, and adapted to mesh alternately with a gear on the feed-shaft, one of said pinions engaging a pinion 70 on the driving-shaft, and the other an idle-pinion, which engages said driving-shaft pinion. 75

4. In an apparatus for turning wrist or crank pins, the combination, substantially as set forth, of a frame, a driving-shaft, a pinion fixed thereon, a feed-shaft, and a gear fixed thereon, a double-armed shifting-lever journaled on the driving-shaft, two driving-pinions mounted on opposite arms of the shifting-lever, and adapted to mesh alternately with the gear of the feed-shaft, one of said pinions engaging the driving-shaft pinion, and the other an idle-pinion meshing with said driving-shaft pinion, a stud fixed to the frame and 80 passing through a segmental slot in the shifting-lever, and a clamping-nut engaging a thread 85 on said stud, and adapted to maintain the shifting-lever in position to engage either of its driving-pinions with the feed-shaft gear. 90

DANIEL W. PEDRICK.
